ELECTRICAL SYSTEM

Daniel W. Hinkel, Pittsburgh, Pa.

Application June 1, 1935, Serial No. 24,545

4 Claims. (Cl. 177—7)

My invention relates to electrical systems for household appliances and particularly to combinations of signaling devices, such as door-bells and lights, and sound-producing apparatus, such as radio receiving sets, vacuum cleaners, washing machines, ironing machines, etc.

It is a common occurrence to have visitors push one's door-bell button, the bell not being heard because of the operation within the house of a radio receiving set, vacuum cleaner, washing machine, ironing machine or other sound-producing apparatus at the time. Moreover, if the ringing of the door-bell is suspected and the radio is turned off in order to listen, then the tubes get cold and possibly a very interesting part of the program is unnecessarily lost before the tubes can be reheated after again throwing the switch.

One object of my invention, therefore, is to provide apparatus for causing cessation of such sound-producing or other electrical apparatus whenever the door-bell button is pushed to ring the bell, such apparatus immediately and automatically resuming its normal operation as soon as the bell button is released. The value of my invention to deaf people or to those holding parties with considerable conversation or other noise going on, or in the case of a housewife being down the cellar operating the washing or ironing machine, is very obvious, inasmuch as the sound from the radio or washing machine, for example, is shut off during the time that the door-bell button is pushed, so that the ringing of the door-bell may be clearly heard, or, in the case of very deaf people, the cessation of motion, light (or other result of the application of electrical energy) in the apparatus in use at the time that the door-bell button is pushed, will act as a signal.

Another object of my invention is to provide a simple and inexpensive auxiliary or accessory apparatus in the form of a small relay so connected to the door-bell and the radio receiving set, or the like, as to shut off such sound-producing apparatus only during the period when the button is pushed.

My invention may be best understood by reference to the accompanying drawing, wherein:

Figure 1 is a diagrammatic view of a system embodying a radio receiving set and a door-bell coordinated in accordance with my present invention;

Fig. 2 is a view, partially diagrammatic and partially in elevation and section, showing the application of my present invention to a vacuum cleaner, and

Fig. 3 is a partially diagrammatic and partially sectional view of a modified form of relay which may be utilized in lieu of the relay shown in Figs. 1 and 2.

Referring to Fig. 1 of the drawing, the system there shown comprises suitable electrical supply circuit conductors 1 and 2, which in the usual case will be the ordinary house 110-volt supply circuit, for energizing the windings of an ordinary bell-ringing transformer 3 for operating a door-bell 4 when a push-button 5 is operated, the system of Fig. 1 also showing a radio receiving set 6 and a relay 7 for coordinating the operation of the door-bell 4 and the radio receiving set 6 in such manner that only one thereof may be operated at any one time, as subsequently described in detail.

The bell transformer 3, door-bell 4, push-button 5 and radio receiving set 6 may be of any well known type, the usual operating switch 10 being provided in the radio 6, and need no further description here. It should be noted, however, that the door-bell 4 is merely illustrative and that any other form of signalling device, such as a light, may be employed, if desired. Moreover, in lieu of the particular type of sound-producing apparatus shown as a radio receiving set 6 in Fig. 1, other sound-producing devices, such as vacuum cleaners, washing machines, ironing machines, etc., may be utilized in coordination with the signalling device 4. The application of my invention to one of these other sound-producing devices, namely, a vacuum cleaner, is illustrated in Fig. 2 and will be later described.

The coordinating device or relay 7 is shown as comprising a suitable casing or cover 11 which may be made in two parts 11a and 11b, for example, suitably screwed or otherwise fastened together and containing a suitably insulated actuating coil 12 for operating a core or plunger 13 which is biased to the illustrated right-hand or circuit-closing position by means of a suitable spring 14 operating within a sleeve or hollow boss 15 integrally or otherwise secured to one end of the casing 11.

The free end of the core or plunger 13 is provided with a resilient contact finger or the like 16 mounted on a suitable insulating block 17 for co-operating with a stationary contact member or terminal 18 mounted on an insulating block 19, which is suitably secured to one member 11b of the casing 11. Four conductors, numbered 23 to 26, inclusive, enter the casing 11 through suitable bushings 20. The connections of these conductors will shortly be described. It will be appre-

ciated that the relay device 7 may be relatively small in size, inasmuch as it is called upon to handle only small currents, and could, therefore, be readily built in or otherwise incorporated within the box or casing of the radio receiving set 6, particularly as only two extra wires are required in addition to the ordinary wires to the radio, which extra wires, 23 and 24, are to be connected in the basement or elsewhere across the terminals of the door-bell 4.

It will be noted that the connections of the bell-ringing transformer 3, door-bell 4 and push-button 5, therefore, are of the standard character and that conductors 23 and 24, leading to the terminals of the relay coil 12, are connected in parallel relation to conductors 21 and 22, leading to the terminals of the actuating coil of the door-bell 4, or, in other words, the relay coil 12 is shown as connected in parallel-circuit relation to the actuating coil of the door-bell 4. While this is the preferable connection since no change is needed in the bell circuits, it would, of course, be possible to utilize my invention with the actuating coil 12 of the relay 7 in series circuit relation with the actuating coil of the door-bell 4. However, this, of course, would impress a lower voltage than normal on the standard door-bell coil and, for this reason, the illustrated parallel connection is preferable. It will also be understood that any suitable direct-current type of door-bell circuit may be utilized, if desired, in lieu of the illustrated alternating-current type of circuit.

One of the wires leading from the supply circuit to the radio receiving set 6 is divided into two conductors 25 and 26, conductor 25 entering one of the bushings 20 and being connected to the stationary contact member 18 within the relay 7, while the other conductor 26 enters another bushing 20 and is connected to the movable contact member or finger 16. By reason of the spring 14 normally urging the plunger 13 into its illustrated extreme right-hand position where contact members 16 and 18 engage each other, it is clear that under normal conditions the relay 7 interposes no changes in the circuit of the radio receiving set, which may be operated in the usual manner by flipping the switch 10.

However, when the push-button 5 is pressed, thereby supplying energy to the coil of the door-bell 4 from the bell-ringing transformer 3 in the ordinary manner, conductors 23 and 24 are also energized through the bell-ringing transformer 3 and push-button 5, thus energizing the actuating coil 12 of relay 7 to pull plunger 13 to the left against the pressure of helical spring 14. Consequently, movable contact member 16 is removed from engagement with stationary contact member 18, and the circuit to the radio receiving set 6 is interrupted instantaneously with the first ringing of the door-bell 4. As a result, the radio receiving set 6 is silent while the bell is ringing, thus permitting those in the house to hear the bell as clearly as would be the case if the radio receiving set had not been in operation. However, as soon as the usual short period of pressure on the push-button 5 is terminated, the circuit to the radio receiving set 6 is again automatically closed by reason of spring 14 urging plunger 13 into its illustrated circuit-closing position to effect engagement between contact members 16 and 18, and the radio receiving set will immediately pick up the program again since there has not been time for the tubes in the receiving set 75 to grow cold.

If a visitor sees fit to press the push-button more than once, the above-noted operations repeat themselves, so that the bell always rings without any sound from the radio receiving set occurring at the same time, and vice versa the radio 5 operates in the normal manner whenever the bell stops ringing. In this manner, concurrent operation of the two devices, one a signalling device and the other a sound-producing apparatus, is precluded through the use of my invention, but 10 the device which is in continuous use, such as the radio, is interrupted only during the precise period that the device which is in temporary use, namely, the bell, is operated.

It will be understood that the normally closed 15 circuit to the radio illustrated in Fig. 1, embodying contact members 18 and 18, may be replaced, if desired, by a normally open circuit which is closed when the door-bell rings to short-circuit the audio circuit to the loud speaker, for example, and thereby effect the same result as the illustrated system, which, however, is the preferred form in the majority of cases.

In Fig. 2, I have illustrated the application of my invention to a motor-driven device which has 25 been selected as a vacuum cleaner, although it will be obvious that the same type of application may be made in connection with washing machines, ironing machines or other motor-driven appliances in the home.

A vacuum cleaner motor is diagrammatically illustrated at 30, it being understood that this representation is intended to be illustrative only and that any type of electric motor suitable for any given application may be utilized.

A grip 31, handle tube 32 leading to the vacuum cleaner motor casing (not shown) and switch 33 for starting and stopping the vacuum cleaner motor 30 are illustrated; all of these may be of a familiar type. As indicating the ready adaptability and simplicity of my present invention when applied to a device of this general character, I have shown my relay device 7 as secured to the tube 32 of the vacuum cleaner handle by means of right-angle metal strips 34, the respective legs of which may be riveted or screwed to the tube and the casing 11 of relay 7, as will be readily appreciated.

It will be noted that the vacuum cleaner motor 30 occupies the same position in the circuit of Fig. 2 as the radio receiving set 6 does in the system of Fig. 1, so that it is unnecessary to completely illustrate the connections of the parts of the electrical portions of relay 7. The illustrated showing is believed to be adequate for the purpose in that conductors 23 and 24, as in Fig. 1, lead to the terminals of relay coil 12, while conductors 25 and 26 lead from one terminal of the motor 30 and from one supply circuit conductor 1 to the cooperating contact members 16 and 18, while conductor 27 leads from the other terminal of the vacuum cleaner motor 30 to the other supply circuit conductor 2.

In addition to conveniently mounting relay device 7 on the tube 32 of the vacuum cleaner handle, the various wires leading into the relay device may be disposed within the tube 32, as illustrated, conductors 23 and 24 passing through an opening in the wall of the tube and being incorporated in a cable 35 in conjunction with the two wires 26 and 27 leading from the supply circuit into the vacuum cleaner switch 33 in the ordinary way. It will be noted that these wires 26 and 27 are marked with a legend "Across supply circuit", while the other conductors 23 and 75

24 are marked with a legend "Across terminals of door-bell". The necessary connections to these four wires may be made in any suitable manner which it is believed need not be described 5 in detail here.

The operation of the vacuum cleaner apparatus illustrated in Fig. 2 corresponds to the previously described operation of the apparatus shown in Fig. 1, namely, operation of the vacuum cleaner motor 30 may be effected in the usual way by merely flipping the switch 33 to its closed position, but upon operation of door-bell 4, the relay 7 operates to open the circuit of conductors 25 and 26, thus shutting off the operation of vacuum cleaner motor 30 to eliminate the sound produced by the vacuum cleaner during the period when the door-bell 4 is ringing. However, upon release of pressure from the push-button 5 and consequent cessation of the ringing 20 of the bell, conductors 25 and 26 are again connected together and the operation of the vacuum cleaner motor 30 is resumed.

Fig. 3 illustrates a modified form of the relay 1 that is shown in Figs. 1 and 2, the structure 25 of Fig. 3 comprising a suitable casing 40 similar to the casing 11 of Fig. 1, within which is disposed a contactor 41 adapted to operate in a substantially vertical line and comprising an actuating coil 42, a core or plunger 43 and a contact disc or bridge 44 of a familiar type, which, in the normal or closed position of the relay, bridges stationary contact members 45 and 46 30 constituting terminals to which conductors 25 and 26 passing through bushings 20 are connected.

It will be appreciated that the illustrated position of relay 41 in Fig. 3 with a circuit completed between conductors 25 and 26 corresponds to the normally closed circuit between these conductors in Fig. 1, the biasing effect of gravity 40 with respect to closing this circuit in the device of Fig. 3 corresponding to the pressure of spring 14 in the device of Fig. 1.

However, upon energization of actuating coil 42 of Fig. 3, the movable contact member 44 is raised, thus interrupting the circuit between conductors 25 and 26 in the same manner that the circuit is interrupted between contact members 16 and 18 in relay device 7 of Fig. 1 when its actuating coil 12 is energized.

It will be seen, therefore, that I have provided a relatively simple and inexpensive device of small dimensions which may be readily incorporated in or attached to a sound-producing apparatus, such as a radio receiving set, vacuum cleaner, washing machine or ironing machine, etc., for stopping the operation of such apparatus and, therefore, eliminating the sound produced thereby during the period when a signalling device, such as a door-bell, is operated. The advantages of this combination of apparatus are obvious and have previously been set forth in some detail.

While I have shown two different forms of my present invention, I do not desire to be restricted to the specific structural details or circuit connections illustrated herein, as various other modifications thereof may be effected without departing from the spirit and scope of my invention. I desire, therefore, that only such limitations shall be imposed thereon as are indicated in the appended claims.

I claim as my invention:

1. The combination with an electrical sound producing device, of an electrical supply circuit, a door bell having an energizing coil, a bell switch for connecting said bell coil to said circuit, relay means connected with said bell circuit to 15 be energized during the period that the bell is energized, a circuit including the electrical sound producing device controlled by said relay means, when the latter is energized, for opening the circuit to the sound producing device, whereby 20 the sound emanating from said device is silenced during the period of ringing of the bell.

2. The combination with a radio receiver, of an electrical supply circuit, a door bell having an energizing coil, a bell switch for connecting 25 said bell coil to said circuit, relay means connected with said bell circuit to be energized during the period that the bell is energized, a circuit including the radio receiver controlled by said relay means, when the latter is energized, 30 for opening the circuit to the radio receiver, whereby the sound emanating from said radio receiver is silenced during the period of ringing of the bell.

3. The combination with a vacuum cleaner, of 35 an electrical supply circuit, a door bell having an energizing coil, a bell switch for connecting said bell coil to said circuit, relay means connected with said bell circuit to be energized during the period that the bell is energized, a 40 circuit including the vacuum cleaner controlled by said relay means, when the latter is energized, for opening the circuit to the vacuum cleaner, whereby the sound emanating from said vacuum cleaner is silenced during the period of ringing 45 of the bell.

4. The combination with an electrical sound producing device, of an electrical supply circuit, a door bell having an energizing coil, a bell switch for connecting said bell coil to said circuit, a 50 relay having an actuating coil connected to said bell circuit for energizing said relay during the period that the bell coil is energized, a circuit including the electrical sound producing device, said relay being operably associated with said 55 last named circuit for opening the latter while the bell coil is energized, whereby the sound emanating from said device is silenced during the period of ringing of the bell.

DANIEL W. HINKEL.
